UNITED STATES PATENT OFFICE.

MARY HUMPHREY ESPEY, OF RISING SUN, INDIANA.

POSTAL CARD.

Application filed April 22, 1924. Serial No. 708,292.

My invention relates to improvements in postal cards and it consists of the constructions and arrangements substantially as herein described and claimed.

An object of the invention is to provide a postal card which has combined therewith the elements of an envelope thereby constituting the card of a postal packet which may contain a gift or message to 10 supplement the greeting printed otherwise applied to the packet either on the front or rear.

A further object of the invention is to provide a combined postal card and envelope, the elements of which bear reciprocal relation to each other, the elements of the envelope serving to conceal an object contained thereby and the elements of the postal card stiffening the envelope to furnish a little 20 extra protection.

A further object of the invention is to provide a device of the character which may contain a Christmas gift, in some instances there being a hole at one edge by 25 which it is readily hung on a Christmas tree.

Other objects and advantages will appear in the following specification, reference being had to the accompanying drawing, in which:

30 Figure 1 is a perspective view of the improved postal card,

Figure 2 is a section on the line 2—2 of Figure 1,

35 Figure 3 is a detail perspective view of the rear of the postal card,

Figure 4 is a detail perspective view of the blank from which the back of the envelope is made.

40 Figure 5 is a perspective view of a postal card having neither hole nor accordion fold,

Figure 6 is a section on the line 6—6 of Figure 5,

Figure 7 is a perspective view of a postal card having a hole but no accordion fold,

45 Figure 8 is a perspective view of a postal card having an accordion fold but no hole.

In carrying out the invention provision is made of a postal card 1 which is nearly similar in all respects to postal cards as 50 commonly known. It is made of a stiff material, cardboard or the like, as is quite customary. At the front there are printed the usual legends 2 relating to the postal address, the matter of correspondence, etc. 55 and greetings 3 appropriate to the occasion which it is intended to celebrate. It

is optional whether the greetings be printed on the front as in Figure 1 or on the back as in Figure 3. Both sides may be printed if desired. 60

A pocket is formed over the entire back of the postal card by means of a paper blank 4 (Fig. 4). This blank is similarly creased at 5, 6 and 7 at opposite sides. It also has a tongue or flap along the bottom 65 edge which is creased at 8, 9 and 10.

These various creases provide an accord- 70 ion fold in the form of an envelope in Figs. 1, 2, 3, 4 and 8 which permits of col- lapsing the pocket or envelope back against

the rear of the postal card, or permits of 75 the extension of the pocket as when con- taining some gift or message written on ad- ditional paper. Those portions of the blank

4 which appear beyond the creases 7 and 10 provide flanges 11 and 12 which are past- 80 ed or otherwise secured to the postal card 1 either on the front surface as shown in Figure 1, or on the back surface. In as- sembling the pocket 4 upon the postal card, 85 the various folds along the bottom edge are suitably tucked under so that a neat, tight and flat arrangement results. This is readily done in practice.

The device is supplemented by a separate 85 closure flap 13 which is creased twice; once at 14 to define a flange 15 and again at 16 to define a cover portion which closes the pocket 4 when extended as in Figure 2.

A hole 17 is punched at one edge of the 90 postal card, for permitting attaching the package on a Christmas tree as illustrated in Figure 7, when so desired. The hole may be omitted if desired as shown in Fig. 8. 95 By way of variation the accordion fold may be left off and a plain envelope used as in Figs. 5 and 7. Figure 7 shows a hole used in combination with this type of envelope, while in Figure 5 the hole is omitted.

100 It is intended that the device shall em- body the advantageous features of both a postal card and an envelope. The postal card being made of ordinary stiff material, adds strength to the envelope, and is of es- pecial importance when it is desired to mail some object which requires a little more pro- tection than the ordinary fragile paper envelope affords. 105

The envelope or packet furthermore af- 110 fords means for sending an additional gift. This may be money, a handkerchief, etc., or it may be a written message to supple-

ment the one already printed on the postal card either front or back. Use is made of flaps 13 to close the envelope, and if it is so desired, the edge of the flaps may be 5 gummed so that it may actually be sealed. The provision of the hole 17, adds a third advantage to the device, namely, that of hanging the packet on a Christmas tree.

The use of the combined envelope and 10 postal card is not confined to any particular use or any particular purpose, the Christmas, Easter, and other seasons, as well as birthdays, etc. being the various occasions to which the postal card is adaptable. It 15 should also be quite obvious that the particular manner of cutting the component parts and assembling them is variable. The device may be made in various sizes and in different ways as proposed in Figures 5 to 20 8, inclusive, and still keep within the spirit of the invention.

I claim:—

A container consisting of a relatively stiff 25 cardboard front and a one-piece back comprising a main portion corresponding in

size and shape to the cardboard front, and having at its sides accordion folded wings provided at their free edges with flanges overlying or overlapping the cardboard front at the ends thereof and adhesively 30 secured thereto and also provided with an accordion bottom flap overlying the lower edge of the carboard front, said side and bottom flaps forming a frame-like finish 35 along the base and side edges of the card- board front, and a closure flap made sepa- rate from the front and back and having one edge adhesively secured along the outer side of the upper edge of the cardboard front and a portion adapted to be extended 40 over the open mouth of the pocket formed by the front and back and accordion ends, and adapted to overlie the upper edge and be adhesively secured to the main portion of the back, completing a frame-like finish 45 around the margin of the cardboard front and permitting a reasonable adjustment of the container for different quantities of filling as and for the purposes set forth.

MARY HUMPHREY ESPEY.
